UNITED STATES PATENT OFFICE.

FREDERICK S. ANABLE, OF BROOKLINE, MASSACHUSETTS, ASSIGNOR TO NATIONAL BINDING MACHINE COMPANY, OF BOSTON, MASSACHUSETTS, A CORPORATION OF MAINE.

STRIP-SERVING DEVICE.

1,195,894.

Specification of Letters Patent. Patented Aug. 22, 1916.

Original application filed August 19, 1908, Serial No. 449,320. Divided and this application filed December 19, 1914. Serial No. 878,152.

To all whom it may concern:

Be it known that I, FREDERICK S. ANABLE, a citizen of the United States, and a resident of Brookline, in the county of Norfolk and State of Massachusetts, (whose post-office address is 53 State street, Boston, Massachusetts,) have invented an Improvement in Strip-Serving Devices, of which the following description, in connection with the accompanying drawings, is a specification, like characters on the drawings representing like parts.

This invention relates to devices or apparatus for supplying strips of paper or the like employed for wrapping or binding packages or for use as labels of any desired length, and has particular reference to that type of apparatus employing a support for a coil of paper strip previously gummed and then dried, and having provisions for moistening the gum upon the strip as the latter is drawn from its coil.

It is apparent that an ungummed strip of paper or the like may be employed, in which case the moistening device for the strip suitably positioned with respect thereto would contain an adhesive instead of water.

This application is a division of my pending application Serial No. 449,320, filed August 19, 1908.

In order that the principle of the invention may be clearly understood, I have disclosed a single embodiment thereof in the accompanying drawing, wherein—

Figure 1 is a side elevation of a strip serving device embodying one form of my invention; Fig. 2 is a plan view of a portion of the device shown in Fig. 1.

The strip support is represented at 1, it being of any suitable construction and being preferably a case wherein a roll of paper may be suitably supported and tensioned. Herein it is represented as mounted upon a base 2. Suitably secured to the base is a reservoir 3 having therein or operatively related thereto a moistener 4 of any suitable construction. Herein the moistener is represented as a wicking having its ends depending into the tank or reservoir. In the form of the invention herein shown the moistener is supported by a spring 5 which normally projects the same toward the service path of the strip, but upon the application of spring pressure to the moistener the

spring 5 yields and the moistener is moved downwardly from the normal service path of the strip. Any other suitable form of moistening device may, however, be employed. A suitable severing device is employed, which is herein shown as a blade 6 positioned between the moistener and the strip support. If desired and as here shown the severing blade and the moistener are so related that during the moistening operation, the blade is guarded by the moistener. This however, is not necessary within the scope and purpose of my invention.

Referring to that embodiment of the invention wherein the blade is guarded by the moistener, I have provided suitable means whereby when the moistener is subjected to strip pressure, it is depressed or moved from its normal position and the blade 6 is thereupon exposed so that the strip is severed.

Irrespective of the particular form and relation of the moistener and severing blade, I employ suitable means to retract the strip after the severing operation. The retractor employed for this purpose is positioned between the strip support and the moistener and operates to draw the strip longitudinally of itself away from the moistener after the severing operation. For this purpose I have herein provided levers 7 pivoted at 8 upon the reservoir and preferably having strip holding members, herein shown as rolls 9, 10, adjustably spring pressed toward each other. To the lower ends of the lever 7 are connected springs 11, whose opposite ends are adapted to be suitably connected to pins 12 extending from the walls of the reservoir 3. If desired, stops 13 may be employed to limit the swinging movement of said levers.

It will be observed that the retractor, herein comprising the lever 7, operates to draw the strip longitudinally of itself away from the moistener after strip severance. So far as I am aware, I am the first in this art to employ a retractor acting to move the strip in its service path away from the moistener after strip severance.

Having thus described one illustrative embodiment of my invention, I desire it to be understood that although specific terms are employed, they are used in a generic and descriptive sense and not for purposes of limitation, the scope of the invention being set forth in the following claims.

Claims:

1. In a machine of the character described, the combination of a container for a roll of gummed tape, a moistener, a retractor intermediate the said container and the said moistener, and operating to draw the tape longitudinally thereof away from the moistener.
2. In a machine of the character described, the combination of a container for a roll of gummed tape, a moistener, a strip severing blade between the moistener and the container, and a retractor intermediate the said container and the said moistener, and operating to draw the tape longitudinally thereof away from the moistener after the severing action.
3. In a machine of the character described, a strip support, a moistener, and a retractor operating to draw the strip longitudinally from the moistener.
4. In a machine of the character described, a strip support, a moistener, a severing device, and a retractor operating to draw the strip longitudinally from the moistener.
5. In a machine of the character described, a strip support, a moistener, and a retractor intermediate the said support and the said moistener and operating to draw the strip longitudinally from the moistener.
6. In a machine of the character described, a strip support, a moistener, and a coöperating strip retractor located to move the free end of the strip to such position between the strip support and the moistener that such free strip end is out of moistening relation to the moistener.
7. In a machine of the character described, a strip support, a moistener, a severing device, and a coöperating strip retractor located to move the free end of the strip to such position between the strip support and the moistener that such free strip end is out of moistening relation to the moistener.
8. In a machine of the character described, a strip support, a moistener, a severing device in the rear of the moistener and a strip retractor 7 located to move the free end of the strip to such position between the strip support and the moistener that such free strip end is out of moistening relation to the moistener.
9. The improved moistener comprising a container for a roll of gummed tape, moistening means, and a retractor comprising a member movable along the path of the gummed tape when it is drawn out and operating to draw the tape longitudinally thereof away from the moistener upon strip severance.

In testimony whereof, I have signed my name to this specification, in the presence of two subscribing witnesses.

FREDERICK S. ANABLE.
